UNITED STATES PATENT OFFICE.

EUGENE O. KROELLS, OF PASO ROBLES, CALIFORNIA.

SLEEVE PULLER FOR AUTOMOBILES.

Application filed September 13, 1926. Serial No. 135,261.

My invention relates to a tool for removing a sleeve from an automobile differential housing in which axle roller bearings run, with or without axle, and the objects of my invention are: To provide for a simple, inexpensive, quick-acting sleeve puller, which consists of a sliding hammer attached to a one-piece steel or iron sleeve puller bar combined with a handle and stop for said sliding hammer to strike against; a hook bent on opposite end to enter in the sleeve hole, and held in by said axle; a bracket in combination with said sleeve puller for removing said sleeve from housing when the axle is out of the housing; said bracket has a curved back to fit against the sleeve puller bar. Said bracket has two different sizes of L's bent on each end of said bracket to be used for different sizes of sleeves. Said sleeves can be removed from either end of said housing without the axle in the housing. Said L's on said bracket are slightly curved to fit evenly against the walls of said sleeves to hold the hook firmly in the sleeve hole.

I attain these objects by the means illustrated in the accompanying figures, in which—

Figure I is a back view of differential housing with the axle in said housing, and a side view of said sleeve puller in pulling position.

Figure II is a back view of differential housing without said axle in said housing, and a side view of said bracket and said sleeve puller in pulling position.

Figure III is a side and general view of said bracket showing curved back and curved L's.

Figure III is a side view of said sleeve puller and hole lengthwise through sliding hammer.

In said drawing marked Figure I, the differential housing is marked 1; 2 is a rear axle; 3 is a roller bearing sleeve; 4 is a hole in roller bearing sleeve, which lines up with grease cup 5; 6 is a sliding hammer; 7 is a sleeve puller bar; 8 is a handle; 9 is a sliding hammer stop and 10 is a hook.

In said drawings Figure II is a bracket curved at 11, bearing against sleeve puller bar at 7^a. 12 is a small curved L bearing against roller bearing sleeve 3^a. 10 is a hook entered in roller bearing sleeve hole 4^a. 13 is a large curved L.

Having described my invention I claim as new:

A sleeve puller comprising a bar, a hammer slidably mounted on the bar, said bar having a hammer-stop on one end, and a hook on the opposite end of the bar from the hammer-stop, in combination with a bracket having an L on one end adapted to rest on the end of the sleeve and a shorter L on the other end of the bracket adapted to fit within the sleeve to hold the bracket against the bar, whereby the hook is held firmly in the sleeve hole.

EUGENE O. KROELLS.
